UNITED STATES PATENT OFFICE.

HORMIDAS S. MIRANDETTE, OF SPENCER, MASSACHUSETTS, ASSIGNOR TO UNITED SHOE MACHINERY COMPANY, OF PATERSON, NEW JERSEY, A CORPORATION OF NEW JERSEY.

CANVAS LAYING AND CREEASING MACHINE FOR INSOLES.

1,236,467.

Specification of Letters Patent.

Patented Aug. 14, 1917.

Application filed January 18, 1911. Serial No. 603,283.

To all whom it may concern:

Be it known that I, HORMIDAS S. MIRANDETTE, a citizen of the United States of America, residing at Spencer, in the county of Worcester and State of Massachusetts, have invented certain new and useful Improvements in Canvas Laying and Creasing Machines for Insoles, of which the following is a specification.

- 10 This invention relates to machines for making soles and particularly to such machines provided with means for laying and creasing reinforcing fabric which has been roughly applied to the soles.
- 15 In making reinforced soles the operations on the reinforcing fabric include a preliminary forming-in or setting of the fabric in the angle at the inner side of the rib, and in some cases a later beading of the fabric 20 about the rib. The machine embodying the invention will be described as performing the forming-in operation, and will be illustrated as operating on what is known commercially as a "Gem" insole, on which the 25 later beading operation is carried out, but it should be understood that the invention is not limited to making "Gem" insoles as it is equally useful in making "Economy" insoles, or any other type of sole to be reinforced 30 wherein the reinforcing fabric is to be secured at the inner side of a marginal lip or rib.

The object of the present invention is to provide a simple machine for applying reinforcing fabric to ribbed soles, and especially for creasing or forming-in the fabric in the angle inside of the lip.

In accordance with this object one feature of the invention contemplates a construction which will hold a sole of a shoe on a table, means being provided for rotating the table and means being also provided for co-acting with the table for creasing a layer of canvas to be used on the ribbed face of the 45 sole, the said sole being held in place on the table by novel means which prevents upward movement of the sole with relation to the table or displacement thereof with relation to the tool used in the operation of 50 creasing the canvas layer.

A still further feature of the invention contemplates the provision of novel means for driving the creasing implement and the sole retaining mechanism simultaneously 55 with the table thereby guarding against the

formation of folds in the canvas layer or damaging the material being treated.

With the foregoing and other objects in view, the invention consists in the features of construction and in the arrangement and 60 combination of parts hereinafter more fully set forth and claimed.

In describing the invention in detail, reference will be had to the accompanying drawings illustrating the preferred embodiment of the invention, wherein like characters denote corresponding parts in the several views, and in which—

Figure 1 illustrates a view, in elevation, of a machine embodying the invention; 70

Fig. 2 illustrates a detail view of the tools of the machine, with a sole in operative position;

Fig. 3 illustrates a perspective view of the canvas supporting guard; 75

Fig. 4 illustrates a plan view of the sole with the canvas applied; and

Fig. 5 illustrates a sectional view of the sole on the line A—B of Fig. 4. 80

In the embodiment of the invention illustrated in the drawings 6 denotes a base, 7 a standard having a bearing 8 thereon in which the power shaft 9 is rotatable, the base 6 also supporting a bearing 10 in which the forward end of said shaft 9 is journaled. 85

The power wheel 11, on the shaft 9, is driven in any appropriate way and a gear wheel 12 is also mounted on the shaft 9 and meshes with a gear wheel 13 on a shaft 14, which shaft 14 also carries a pulley 15 and 90 a second gear wheel 16.

An arm 17 has one end supported by the standard 7 to which it is connected by a pivot 18 and a bearing 19 is formed on the arm in which the shaft 14 is journaled. The 95 arm 17 has an extension 20, forming the journal bearing for a shaft 21 carrying an idler 22. A belt 23 is run over the idler 22 and over the pulley 15 for the purpose of driving a shaft 24 through the medium of 100 the pulley 25 which is mounted thereon. The shaft 24 is journaled in a sleeve 26 pivoted on a bracket 27 which is adjustably mounted through a medium of the slot 28 and co-operating set screw 29, on the forward 105 end of the arm 17.

The shaft 24 carries on its lower end a canvas creasing tool 30 which is yieldingly held in a sleeve 26 by means of the spring 31 which encircles the shank of the tool 30 110

and bears against the lower end of the sleeve 26 and against a collar 30^a on the said shank. The sleeve is mounted on a pivot 32 in the bracket 27 and can be moved about said pivot for the purpose of changing the angle of inclination of the tool 30 with relation to the work table 33 which is rotatable in a standard 34 rising from the base 6. The angle of inclination is determined by adjustment of a set screw 27^a carried by the bracket 27 and bearing against the sleeve 26.

The under surface of the table has a beveled gear wheel 35 meshing with a gear wheel 36 on the shaft 9 and, therefore, the table is rotated under the influence of the shaft 9 to feed the sole. The arm 17 has a spring 37 connected to it, the said spring being also attached to the base 6, for automatically adjusting the said arm 17 with relation to the table. The arm 17 is furthermore provided with a link 38 which is connected to a lever 39 pivoted on the journal bearing 10 and having an operating rod 40 by which the said lever is oscillated for moving the arm 17 away from the table against the action of the spring 37.

A shaft 41 is journaled in a downwardly extending portion of the arm 17 and has a beveled gear wheel 42 thereon which meshes with a beveled gear wheel 43 mounted on a shaft 44 which shaft is journaled in a bearing 45 formed on a forward extension of the arm 17. The shaft 41 is driven by a gear wheel 41^a which meshes with the gear wheel 16. The end of the shaft 44 remote from the gear wheel 43 is provided with a work engaging disk 46 which coacts with the table for the purpose of feeding the sole 47 past the tool 30 and with the tool 30 for tightening the canvas against the lip or rib of the sole.

A guard 48 is pivotally connected to the arm 17 and extends over the disk 46 and partially over the table 33 and is designed to coöperate with the tools for the purpose of supporting the free margin of the reinforcing material while under treatment so that the same shall not contact with the rotating presser. As shown in Fig. 3, the guard 48 has apertured ears 49 by which it is connected to the arm 17.

In practice, a sole such as is shown at 47, which has been fitted as shown in cross section in Fig. 5, and had the canvas 48^a roughly applied thereto is placed on the table 33 under the tools 30 and 46 which are raised from the table by lifting the arm 17. Owing to the rotation of the disk which co-acts with the table, the sole is moved with relation to the tool which, being rotated at an angle with relation to the table, acts on the canvas layer which has been roughly applied to the sole and creases it or forms it in, at the inside angle of the lip.

It has been found in practice that a machine embodying this invention is efficient in pressing the canvas closer against the surface of the sole of the shoe, at the same time creasing the said canvas and causing it to adhere to the said sole. 70

I claim:

1. In a canvas laying and creasing machine, a rotatable table, an arm pivotally mounted with relation to the table, a sleeve, 75 a bracket on which the sleeve is pivotally mounted, means for adjustably mounting the bracket on the arm, a guard projecting from the arm for supporting the canvas, a disk for engaging the sole under treatment, 80 and means for rotating the table, disk and creasing tool in unison.

2. In a canvas laying and creasing machine, a rotatable table, an arm pivotally mounted with relation to said table, a 85 bracket adjustably secured to said arm, a sleeve supported on said arm by said bracket, a creasing tool mounted in said sleeve to operate obliquely with relation to the surface of the table, means for holding the creasing tool in engagement with the material under treatment, a rotary disk coacting with the table, a guard comprising a curved body portion, apertured ears extending from said body portion and adapted to connect the said 95 guard with the arm, and means for rotating the creasing tool.

3. In a canvas laying and creasing machine, a rotatable table, an arm pivotally mounted with relation to said table, a bracket 100 adjustably secured to said arm, a sleeve supported on said arm by said bracket, a creasing tool mounted in said sleeve to operate obliquely with relation to the surface of the table, a spring for holding the creasing tool 105 in engagement with the canvas, a rotary disk coacting with the table, a guard projecting from the arm for supporting the free margin of the canvas above said rotary disk, and means for rotating the creasing tool. 110

4. In a canvas laying and creasing machine, a rotatable table, an arm pivotally supported with relation to said table, means on the arm for supporting a creasing tool, means for adjusting the tool to various 115 angles, a disk rotatably supported by the arm, and a guard secured to the arm, said guard adapted to support the free margin of the canvas.

5. In a canvas laying and creasing machine, a rotatable table, a tool carrying arm, 120 a bracket on the arm, a sleeve pivotally supported by the bracket, a creasing tool rotatable in the sleeve, means for adjusting the tool to different angles, means for operating 125 the creasing tool, and means for holding the tool in engagement with the canvas.

6. In a device of the character specified, a frame an arm hinged to said frame, two rotatable shafts mounted on said arm, a form- 130

ing-in roll mounted on one of said shafts, a rib-tightening roll mounted on the other of said shafts, a feed member adapted to co-operate with said rolls, and means whereby 5 said rolls and said feed member may be actuated.

7. A machine for forming-in reinforcing fabric at the inside angle of a ribbed sole to which the fabric has been roughly applied, 10 plied, having, in combination, a rotary fabric forming-in tool inside of the rib, a co-operating rotary tool outside of the rib, means opposite said forming-in tool for engaging and supporting the free margin of 15 the fabric to prevent improper application thereof by the forming-in tool, and means for supporting the sole with its rib between said tools.

8. A machine for forming-in reinforcing fabric at the inside angle of a ribbed sole to which the fabric has been roughly applied, having, in combination, a forming-in roll inside the rib, a rib-tightening roll outside the rib, a tool arranged above the rib- 20 tightening roll to support the free margin of the fabric and hold it from being caught by said rolls, and means for supporting the sole with its rib between said rolls. 25

9. A machine for forming-in reinforcing

fabric at the inside angle of a ribbed sole to 30 which the fabric has been roughly applied, having, in combination, a forming-in roll inside the rib, a rib-tightening roll outside the rib, a guard plate arranged beneath the fabric to hold its free marginal portion from 35 being caught by said rolls, and means for supporting the sole with its rib between said rolls.

10. A machine for forming-in reinforcing fabric at the inside angle of a ribbed sole to 40 which the fabric has been roughly applied, having, in combination, a rotatable sole supporting table, an arm pivotally mounted with relation to said table carrying a sleeve, a rotary forming-in tool mounted in said 45 sleeve to operate obliquely with relation to the surface of the table, means for holding said tool in engagement with the fabric, a rotary disk co-acting with the table, and a guard above the rotary disk for supporting 50 the fabric.

In testimony whereof, I affix my signature in the presence of two witnesses.

HORMIDAS S. MIRANDETTE.
